UNITED STATES PATENT OFFICE

DANIEL B. WORTH, OF ROCHELLE, ILLINOIS

DESIGN FOR A RAILWAY LOCOMOTIVE

Application filed January 23, 1933. Serial No. 46,940. Term of patent 7 years.

To all whom it may concern:

Be it known that I, DANIEL B. WORTH, a citizen of the United States, residing at Rochelle, in the county of Ogle and State of Illinois, have invented a new, original, and ornamental Design for a Railway Locomotive, of which the following is a specification, reference being had to the accompanying drawing, forming part thereof.

In the drawing—

Figure 1 is a perspective view of a rail-

way locomotive showing my new design with the supporting trucks omitted;

Fig. 2 is a side view indicating the trucks in dotted lines, and

Fig. 3 is an end view having the trucks omitted.

I claim:

The ornamental design for a railway locomotive, as shown and described.

DANIEL B. WORTH.
